CLAIM

The ornamental design for a self cleaning desoldering tool combination or the like, substantially as shown and described.

DESCRIPTION

FIG. 1 is a right side elevational view of a self cleaning desoldering tool combination or the like embodying my new design, the left side elevational view thereof being a mirror image of the illustrated right side;
FIG. 2 is a right side elevational view of the removable upper portion thereof;

FIG. 3 is a top view of the upper portion;

FIG. 4 is a bottom view of the upper portion;

FIG. 5 is a front elevational view of the upper portion;

FIG. 6 is a rear elevational view of the upper portion;

FIG. 7 is a side view of the lower, base portion thereof, the base portion being essentially a figure of revolution about a vertical axis; and

FIG. 8 is a top view of the lower, base portion thereof.
